DEFROSTER CONTROL

Harold S. King, Elkhart, Ind., assignor to Penn
Controls, Inc., a corporation of Indiana

Application July 29, 1948, Serial No. 41,282

13 Claims. (Cl. 62—4)

1

This invention relates to a defroster control of the type wherein a timer operates a by-pass valve for the expansion valve of an evaporator, and a switch at the same time closes for insuring operation of the refrigerant compressor motor when the timer calls for a defrosting operation, hot refrigerant then being pumped through the evaporator for melting the frost therefrom.

One object of the invention is to provide a timer actuated defrosting valve wherein a comparatively heavily loaded spring-closed valve may be opened by a relatively weak motor, such as an electric clock motor.

More particularly it is an object of the present invention to provide a cam moved spring-loaded lever in which the spring can be gradually loaded over a long period of time by the timer motor, and then suddenly released by the cam so that the spring effects opening of a valve of sufficient capacity to serve as an expansion valve by-pass, the timer having further cam actuated means to trip the valve to the off-position after a predetermined relatively short defrosting period, whereupon the return spring of the by-pass valve recloses the valve so that normal refrigeration cycles thereafter occur until another defrosting period is called for by the defroster control.

A further object is to provide a control switch in connection with the timer motor and actuated thereby, which shunts the usual automatic switch provided for the refrigerant compressor motor and insures operation of the refrigerant compressor during the defrosting period, regardless of whether or not the normal control switch is calling for refrigeration.

With these and other objects in view, my invention consists in the construction, arrangement, and combination of the various parts of my device whereby the objects contemplated are attained, as hereinafter more fully set forth, pointed out in my claims, and illustrated in the accompanying drawings, wherein:

Figure 1 is a front elevation of a defroster control embodying my invention and showing it in a normal position, that is, when not calling for a defrosting operation, a refrigerant system and a wiring circuit for the refrigerant compressor motor thereof being shown in conjunction with this figure.

Figure 2 is a similar view omitting the diagrammatic showing and illustrating the defroster control tripped to the operative position.

Figure 3 is a view similar to a portion of Fig-

2

ure 2 showing the parts in the position assumed following the conclusion of the defrosting period.

Figure 4 is an end elevation of the control as viewed from the right hand end of Figure 1; and

Figures 5 and 6 are sectional views on the lines 5—5 and 6—6 respectively, of Figure 4.

On the accompanying drawings I have used the reference numeral 10 to indicate a mounting plate, and 12 a flange extending therefrom on which a by-pass valve V is located. The valve V has an inlet 14, an outlet 16, a valve seat 18, and a valve disc 20.

Extending from the disc 20 is a stem 22 connected with a bellows head 24. A bellows 26 connects the body of the valve V with the head 24 for sealing purposes in the usual manner. A hub 28 extends from the head 24 and an adjusting screw 30 is threaded therein, the screw having a head 32 and being locked at adjusted positions by a nut 34. A return spring 36 is interposed between the body of the valve V and the bellows head 24 for normally closing the valve V as in Figure 1.

I provide mechanism for actuating the valve V comprising a die plate 38 secured to the mounting plate 10 by suitable posts and a series of levers and cams are mounted on the plate 10 and will now be described.

A valve and switch actuating lever 40 is pivoted at 42, has a protuberance 44 adapted to contact the head 32 of the screw 30 and has an insulation extension 46 adapted to actuate a switch S. The spring 36 tends to normally rotate the lever 40 clockwise.

An actuating lever 48 is pivoted at 50 and is normally biased upwardly by a spring 52 connected with one of the posts for supporting the side plate 38. This particular post is indicated at 54.

The lever 48 has pivoted thereto at 56 a pair of links 58 carrying a roller 60 between their upper ends. This roller is adapted to coact with a pair of notches 62 and 64 of the lever 40. The links 58 have a projection 66 to coact with the cam 76 as will hereinafter appear.

A shaft 66 is rotatably mounted and through suitable gearing 68 and 70 is driven at slow speed from an electric clock motor indicated generally at C. The shaft 66 carries a cam 72 of spiral character having a drop indicated at 74. A second cam 76 is carried by the cam 72 and has a drop at 78. The cam 76 is adjustable relative to the cam 72 by being rotatable on the shaft 66 independent of the cam 72. An arcuate slot 80

and a clamp screw 82 are provided to retain the adjustment, whereas a set screw 84 threaded in an ear 86 of the cam 72 and engaging an ear 88 of the cam 76 serves as a means for micro-metrically adjusting the cam 76 in relation to the cam 72.

The switch S comprises a base 92 on which is mounted a stationary contact 94, a movable contact 96, a contact actuating blade 98, a switch actuating blade 100 and a spring-extended toggle link 102 interposed between a pointed element 104 and the blade 98. This arrangement provides for snap action of the switch S.

The by-pass valve V is connected in a refrigeration system as shown diagrammatically in Figure 1, the valve being in parallel with the usual expansion valve EV and condenser C of the system. The condenser of the system is shown at C, the evaporator at E, the refrigerant compressor at 106, and the refrigerant compressor motor at M. The system normally includes an automatic control such as a bellows 108 responsive to low side pressure in the system and operating contacts 110. The contacts 94 and 96 of the switch S are arranged to shunt the contacts 110 as shown.

Practical operation

In the operation of my defroster control the shaft 66 would rotate, for instance, once in 12 hours, although this period may be either shorter or longer if desired. The direction of rotation is counterclockwise.

In Figure 1 it will be noted that the drop 74 of the cam 72 is approaching the right hand end of the actuating lever 48. The valve V is closed. The defrosting period will commence when the drop 74 passes the end of the lever 48. After such passage has occurred as illustrated in Figure 2, the lever 48 is raised by the spring 52 and since the high portion of the cam 76 is against the projection 90 of the links 58, the roller 60 will be thereby held in the notch 62 and rotate the valve and switch actuating lever 40 counterclockwise as illustrated. The relative strengths of the springs 52 and 36 are such that the spring 52 overcomes the spring 36 (the difference in leverage at 44 and 60 aiding in this respect), and the valve V is accordingly opened.

At the same time the switch S is permitted to close by reason of the projection 46 moving toward the right, and the actuating blade 100 of the switch returning to its initial shape as shown in Figure 2. This closes the switch with snap action, and the refrigerant compressor motor M is energized even though the bellows switch 108-110 is not calling for refrigeration. Since the valve V is now open, the hot refrigerant from the compressor 106 will by-pass the evaporator valve EV and the condenser C and flow through the evaporator E for melting the frost therefrom.

Referring to Figure 3, after a few more minutes of operation the projection 90 will fall off the drop 78 of the cam 76, thus permitting the roller 60 to be cammed by a projecting portion 63 of the lever 40 from the notch 62 to the notch 64 as illustrated, and as indicated by the arrow a. This permits the return spring 36 to expand and close the valve V.

The relatively strong spring 52 is now loaded throughout the remaining portion of the timing period by the counterclockwise rotation of the cam 72 which gradually lowers the lever 48 against the bias of the spring 52. This arrangement permits the relatively weak clock motor C

to tension the spring 52 over a long period of time for eventual release again as in Figure 2.

The time for defrosting is represented by the projection 90 dropping off 78 of the cam 76 in relation to the lever 48 dropping off 74 of the cam 72. The drops 90 and 48 may be relatively adjusted for longer or shorter defrosting periods by manipulation of the clamp screw 82 and the set screw 84 in an obvious manner.

A defroster control of the character disclosed permits a relatively rugged by-pass valve V to be operated with all the force necessary, but a relatively light motor, such as one of the electric clock type, is capable of resetting it for the next operation. The parts to accomplish this result are comparatively few and simple to manufacture and assemble.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In a defroster control, a movable control element having a shallow notch and a deep notch, an actuating element having a link pivoted thereto to engage said shallow notch, said notches being so shaped as to bias said link from said shallow notch to said deep notch, a spring to effect engagement of said link with said movable element and move said element to a position actuating said movable element, timer actuated cam means for gradually moving said actuating element back to a position with said spring loaded, and defroster terminating means comprising a second cam engaging said link to normally keep it in the shallow notch and permit it to transfer to the deep notch when the second cam ceases to engage the link.

2. In a defroster control, a movable control element having a shallow notch and a deep notch, said movable element having an operative position for effecting a defroster operation, an actuating element having a link pivoted thereto to engage said notches, said link being normally engaged in said shallow notch, a spring acting through said actuating element to effect such engagement, to bias said link toward said deep notch and to move said movable element to said operative position, cam means for gradually moving said actuating lever back to a position with said spring loaded, and defroster terminating means comprising a second cam carried by the first cam and engaging said link to normally keep it in said shallow notch and to permit it to transfer to said deep notch at a predetermined position of said second cam.

3. In a defroster control, a timer actuated shaft, a spiral cam thereon having a drop, an actuating lever engaging said cam, a spring to effect such engagement, a valve actuating lever having a shallow notch and a deep notch, a link connected with said actuating lever, engaged in said shallow notch by said spring acting through said actuating lever and biased to transfer from said shallow notch to said deep notch by said spring, a second cam on said shaft for retaining said link in said shallow notch against the bias of said spring, said second cam having a drop for permitting the link to drop into the deep notch, and defroster means adapted to be operated by said spring acting on said actuating lever when it drops on said first cam.

4. In a defroster control, a timer actuated shaft, a spiral cam thereon having a drop, an actuating lever engaging said cam, a spring to effect such engagement, a control lever having a shallow notch and a deep notch, a link connected with said actuating lever and biased by said spring acting through said actuating lever to transfer from said shallow notch to said deep notch, a second cam on said shaft for retaining said link in said shallow notch, said second cam having a drop for permitting the link to drop into said deep notch, and a spring-loaded defrosting means adapted to be operated against its spring load by said spring acting on said actuating lever when it drops on said first cam.

5. In a defroster control, a timer actuated shaft, a spiral cam thereon having a drop, an actuating lever engaging said cam, a spring to effect such engagement, a defroster lever having a shallow notch and a deep notch, a link connected with said actuating lever and biased by said spring acting through said actuating lever to engage said notches, said link being normally engaged with said shallow notch but constrained toward said deep notch by said spring, a second cam on said shaft for retaining said link in said shallow notch against the action of said spring, said second cam having a drop for permitting the link to drop into said deep notch, and defroster means adapted to be operated by said spring acting on said actuating lever when it drops on said first cam.

6. In a control of the character disclosed, a defroster control lever biased to move to a normal position, a spring-loaded second lever, a link for operatively connecting said second lever to said defroster control lever to move said defroster control lever under the bias of said spring-loaded lever, a motor driven cam for gradually moving said spring-loaded lever and thereby loading its spring, said cam having a drop for releasing said spring-loaded lever, said spring-loaded second lever thereupon acting through said link to move said defroster control lever, one of said levers having a shoulder against which said link is normally engaged by said spring-loaded lever, and a second cam operable to release said link so that said spring-loaded lever can disengage said link from said shoulder whereby said defroster control lever can be moved by its bias to said normal position for terminating the defrosting period.

7. In an automatic defrost control device for use in a refrigeration system, a valve, a first spring for biasing said valve in a closed position, a second stronger spring capable when stressed and operative when released from a stressed position to open said valve with a snap action against said first spring, a synchronous timer motor, means driven by said motor for stressing said second spring over a period of time and for effecting its release at a predetermined time, a member movable to a first position in which said second spring is rendered operative when released from its stressed position to open said valve and to hold it open, and movable to a second position in which said second spring is rendered inoperative to hold said valve open, whereby said valve may again be closed with a snap action by said first spring, spring means for biasing said member in one position, and means driven by said motor for moving said member to its other position.

8. In an automatic defrost control device for use in a refrigeration system, a valve, a first

spring for biasing said valve in a closed position, a second stronger spring, a synchronous timer motor, means including speed reduction gearing and cam means driven by said motor for building up a stress in said second spring over a period of time and for subsequently effecting its release at a predetermined time, a member movable to a first position in which said second spring is rendered operative to open said valve with a snap action and to hold it open when released from its stressed position, and movable to a second position in which said second spring is inoperative to affect said valve, whereby it may be again closed with a snap action by said first spring, resilient means for biasing said member to one position, and means driven by said motor for moving it to its other position.

9. In an automatic defrost control device for use in a refrigeration system, a valve, a switching device, a first spring for biasing said valve in a closed position, a second stronger spring, a synchronous timer motor, means driven by said motor for building up a stress in said second spring over a period of time and for effecting its release at a predetermined time, a member movable to a first position for rendering said second spring operative when released from its stressed position to open said valve with a snap action and to hold it open, and movable to a second position in which said second spring is inoperative to hold said valve open whereby it may again be closed with a snap action by said first spring, spring means for biasing said member in one position, means driven by said motor for moving said member to its other position, and a member movable with said valve for the actuation of said switching device.

10. In a device of the class described, a control member movable oppositely between two control positions, an actuator therefor, a first spring for moving said control member to a first position, a second stronger spring, an operative connection between said second spring and said actuator, said second spring being arranged to act opposite in relation to said first spring and capable when released after being stressed of moving said control member through said actuator and said operative connection to its second position and holding it there, said second spring having a normal unstressed position in which said first spring is permitted to move said control member to its first position, a timer motor, cam means driven by said motor for stressing said second spring over a period of time and for restraining it while it is being stressed, a second cam means for restraining one element of said operative connection while said second spring is being stressed, said first cam means releasing said second spring at a predetermined time and after said spring has been stressed, whereby to move said control member through said actuator under the action of said second spring, and said second cam means subsequently releasing said element to permit said first spring to move said control member.

11. In a device of the class described, a valve, a first spring for biasing said valve in a closed position, a second stronger spring, an operative connection between said second spring and said valve, said second spring through said operative connection being capable when released after being stressed of opening said valve against said first spring, a timer motor, means driven by said motor for stressing said second spring over a period of time, said means also restraining said second spring while it is being stressed, means

driven by said motor for releasing the energy stored in said second spring at a predetermined time and after said spring has been stressed, one element of said operative connection being movable to a first position by said second spring and operative through another element of said operative connection when the spring is released to open said valve and to hold it open, and movable to a second position in which said second spring is rendered inoperative to hold said valve open, and means driven by said timer motor for moving said one element to a third position at a predetermined time whereby it is subsequently operative to utilize the release of said second spring to open said valve.

12. In a device of the class described, a valve, a first spring for biasing said valve in a closed position, a second stronger spring, an actuating lever to which said second spring is connected, said second spring through said actuating lever being operatively capable of opening said valve and holding it open against said first spring when said second spring is released after being stressed in a direction opposed to said first spring, a timer motor, a shaft driven by said motor, speed reduction gearing between said motor and said shaft, a first cam on said shaft for engaging said actuating lever to move one end of said second spring in a direction and to a position over a period of time wherein it is stressed to oppose said first spring, said cam restraining said actuating lever and thereby said second spring while it is being stressed and subsequently releasing said actuating lever, a member for transferring movement of said actuating lever to said valve, a second cam rotatable with said shaft for restraining said member until after said first cam has released said actuating lever at a preselected time and after said second spring has been stressed, said second cam being rotatable with said shaft and

5 angularly adjustable thereon for releasing said member a preselected interval after the release of said actuating lever whereby said member is subsequently operative to utilize the release of said second spring to open said valve.

13. In a defroster control of the character disclosed, a defroster control lever biased to position for discontinuing a defrost operation, a spring loaded second lever, a link to move said defroster control lever, said link being pivoted to one of said levers, the other of said levers having a double notch with one of the notches deeper than the other, said link normally engaging in the shallower notch and biased by said spring loaded lever toward the deeper notch, a clock motor driven cam for gradually moving said spring loaded lever and thereby loading its spring, said cam having a drop for releasing said spring loaded lever whereupon it is moved by its spring and 10 said link is thereupon moved by said spring loaded lever for moving said defroster control lever against its bias, and a second clock driven motor cam operable to disengage said link whereupon said spring loaded lever moves said link from the 15 shallow notch into the deeper notch for permitting the bias for said defroster control lever to act and thereby terminate the defrosting period.
